(57) **CLAIM**

The ornamental design for a fuel tank and air passage assembly, as shown and described.

DESCRIPTION

FIG. 1 is a perspective view of a fuel tank and air passage assembly showing my new design;

FIG. 2 is a top view of fuel tank and air passage assembly showing my new design;

FIG. 3 is a bottom view of a fuel tank and air passage assembly showing my new design;

FIG. 4 is a front view of a fuel tank and air passage assembly showing my new design;

FIG. 5 is a side view of a fuel tank and air passage assembly showing my new design;

FIG. 6 is the opposite side view of a fuel tank and air passage assembly showing my new design; and,

FIG. 7 is a back view of a fuel tank and air passage assembly showing my new design.

The broken lines in the drawings represent unclaimed environmental subject matter and form no part of the claimed design.
